TELEVISION RECEIVING APPARATUS

Pierre Marie Gabriel Toulon, Puteaux, France

Application January 25, 1937, Serial No. 122,275
In France January 30, 1936

5 Claims. (Cl. 178—7.5)

According to the known methods of electrical transmission of moving images, in order to ensure the continuity of visual impression, a certain number of images is transmitted per second; 5 each image is formed of a certain number of lines and each line is constituted by a certain number of points (image elements). To each image point there corresponds an electrical impulse of a certain amplitude. In the receiving set, this 10 electrical impulse is transformed into a luminous point, the brilliancy of which varies in accordance with its amplitude; this point constitutes one element of the image received.

As transformers of the current into light, a 15 Braun tube is most frequently employed at the present day, in which the luminous point is produced by an electronic beam modulated by the electrical impulse and impinging on a fluorescent screen. The use of luminous discharge tubes, 20 Kerr cells etc. is also known, all these devices transforming the current received into modulated light and usually being combined with mechanical scanning devices, such as Nipkow discs, Weiler drums, etc.

25 In all present day television receivers, this transformation of the current into light is done in an instantaneous manner and the duration of the luminous phenomenon is equal to the duration of the electrical impulse. The present invention has for its object a new method of reception 30 which is characterised by the feature that the duration of the luminous impulse exceeds that of the electric current.

While all present-day receivers are characterised by the direct transformation of the current 35 impulse into a luminous point, according to the present invention there is introduced into the receiver an additional member which is subjected to the action of the electrical impulses and which 40 serves in turn to vary the intensity of the luminous point. This member is arranged and operated in such a manner that it undergoes, under the influence of an electrical impulse, a modification which is a function of the impulse, and 45 this modification is maintained for an interval of time which is longer than the duration of the impulse. Preferably, the arrangements are such 50 that this interval is substantially equal to the time of scanning of the entire image. According 55 to the invention, and due to this collecting member, the result is obtained that the luminous points will maintain their brilliancy for an interval of time which is much longer than in known receivers. If, for example, the image were constituted by 100,000 points, and, if according to

the invention, the brilliancy of a point were maintained throughout the transmission of an image, each point would make an impression on the eye of the observer for a time which is 100,000 times longer than in existing receivers. The 5 image obtained according to the invention will therefore be much more brilliant and will even be suitable for projection onto a screen.

Applied to receivers employing a cathode beam and fluorescent screen, the invention, without 10 sacrificing the luminosity, allows of working with an electronic beam which is relatively little powerful and little accelerated, while in existing 15 Braun tube receivers, it is necessary, in order to ensure a sufficiently luminous image, to bombard 20 the fluorescent screen violently, which deteriorates it and reduces the life of the tube. Attempts have been made in these tubes to increase the optical effect by employing a fluorescent substance having a certain luminous inertia, but 25 this effect necessitates a more intense bombardment of the screen, which is therefore even more detrimental to the life of the tubes; moreover, this property is difficult to adjust and to maintain constant.

25 The second feature of the operation of a receiver according to the invention, that is, the control of the intensity of the luminous points by the collector, may have for result either that the point remains luminous throughout the 30 interval of time elapsing between the transmission of two successive images (arrangements may be made so that its brilliancy remains constant during the whole of this time; in certain cases it may vary progressively).

The invention also offers the advantage of the 35 diminution and even suppression of the flickering effect of the image received. Owing to a certain continuity in the luminosity of the points of the image, it is even possible, without interfering 40 with the optical efficiency and without introducing the phenomenon of flickering, to reduce the number of images transmitted per second and, therefore, to diminish the frequency band for 45 transmission.

The accumulation or, more exactly, the storage 50 of the electrical image impulses on the collecting device may be done in the form of an electric charge (for example, an electronic deposit).

After the accumulation of the electrical 55 impulses on the collector and their transformation into luminous points, the collector is restored to its original state so as to be able to accumulate there the impulses of the following image. This method of clearing may be either instantaneous

(that is, the charge of the collector corresponding to an impulse will be suddenly effaced) or progressive. The instantaneous clearing is preferably effected by the scanning of the collector synchronously with the accumulation of the electrical impulses. The progressive clearing may be effected, for example, by the charge flowing away in a conductor offering a certain resistance.

In the case of accumulation in the form of an electric charge, the collector is preferably constructed in the form of an electrode comprising the same number of cells insulated from one another as the number of points which it is desired to receive per image. These cells are charged one after the other by the electrical image impulses and their charges are transformed into luminous points.

According to a modification of the invention, in the case where it is applied to receivers employing a cathode beam and fluorescent screen, use is preferably made of such a collector comprising multiple elements or cells, and the latter are successively charged by an electronic beam modulated by the electrical image impulses and moving in synchronism with the image analysis at the transmitting station. The cells will maintain their charge for a certain time not exceeding that of the transmission of a complete image, and then by suitable means their charges are caused to disappear and they are rendered suitable to be influenced by the impulses of the following image. The charges acquired by the cells of the collector modulate another stationary electronic beam transversing all the cells simultaneously. This beam impinges on the fluorescent screen and simultaneously produces there as many luminous points as there are cells. The brilliancy of each point will be a function of the charge of the corresponding cell; the effect is maintained while this charge exists. The aggregation of these points will form the image received.

The accompanying drawing illustrates the invention by way of example.

Fig. 1 illustrates the application of the method of accumulation of the signals transmitted, in accordance with the invention, to a cathode-ray tube, by means of an intermediate electrode (collector), on which the electric charges are deposited.

Fig. 2 illustrates, on an enlarged scale, an embodiment of the intermediate collector on which the electric charges are stored. This figure shows how the charges act to modify locally the illumination of the fluorescent screen.

These figures are given only by way of example.

In Fig. 1 there is illustrated, in sectional view, the general arrangement of a vacuum tube provided with two electron guns, the first gun 6 serving to deposit electric charges on the collector 12 and the second gun 22 utilising these electrified charges for producing locally the luminosity of the screen 21.

In this figure, 9 denotes the antenna which receives the transmissions from the radio broadcasting station, 8 the amplifier, and 7 the control grid of the electron gun 6. The electronic lens 10, 11 concentrates the electronic beam to a spot on the electrode 12. The deflecting plates 13 and 14 are connected to a releasing device 15 (of the thyratron type for example) and ensure the scanning of the surface of the electrode 12, which constitutes a collector. The scanning system is synchronized, as is customary, from the

device 8, which receives not only the modulation but also the synchronising signals.

Contrary to the television receiving devices comprising a Braun tube as have been employed up to the present day, the electrode 12 is not covered with fluorescent material and does not serve as a luminous screen, but serves only for the instantaneous accumulation of the signals.

This collecting electrode 12 is composed of a very large number of parallel insulating bands, such as 16, 17, 18 etc. shown in section in Fig. 1, extending perpendicularly to the surface of the drawing. These collecting bands are inclined with respect to the path of the electrons proceeding from the gun 6, so that the electrons emanating from this gun (and controlled by the television amplifier 8) are successively deposited on the different elements of each band in proportion to the scanning. The charges so deposited on each of the parts of the collecting electrode can only flow away slowly, since the bands are good insulators. However, these charges exist only for a certain time. In effect, owing to the slight conductivity of the support and also owing to the very small traces of gas contained in the envelope and the free ions which render the medium conductive, or even by other means which will be hereinafter described, the charges deposited disappear at the end of a certain time so that the quantity of electricity remaining at each point of the collector is substantially a function of the quantity of light at the corresponding point of the televised image; the continual scanning of the surface of the collector by the beam 6 modulated in intensity by the wireless reception has for effect to maintain this correspondence.

It is possible to employ the charges so deposited locally on the collector for controlling the luminosity of the fluorescent screen 21.

To this end, the different bands of the collecting electrode 12 are arranged so that a small interval is left between them. They may be compared to the opened slats of a Venetian blind. Their planes converge towards a geometrical point 22, where a second electron gun is placed. This second electron gun, owing to the accelerating electrodes 18 and 19, furnishes a very intense beam of exactly determined direction. This electron flux cannot be deposited on the insulating supports 16, 17, 18 etc. owing to its orientation, and it is incapable of modifying the distribution of the charges deposited owing to the gun 6. On the contrary, this electron flux coming from the gun 22 is controlled from the point of view of its intensity, at each of the points of its passage across the intervals between the "slats" of the collecting electrode 12, so that the fluorescent screen 21, which receives the electrons of the second beam 22, continuously reproduces the luminous image of the charges deposited on the collector 12, while maintaining their relative position.

Fig. 2 which reproduces, on an enlarged scale, the details of execution of the collecting electrode 12 of Fig. 1 clearly shows how the control of the flux of the second electron gun 22 is effected from the charges deposited. In this figure, there is illustrated at 24, 25, 26 a section of the general conductive mounting which serves as support for the collecting insulating plates 16, 17, 18 (slats of the Venetian blind). There is illustrated by the arrow 6 and by the arrow 22 the orientation, at the outset, of the electrons proceeding from the gun 6 (for scanning the screen 75

(12) and from the gun 22 (causing the illumination of the screen 21). As can be seen in this figure, the constitution of the support 24, 25, 26 is such that the insulating plates are carefully protected against an electron flux proceeding from the gun 22. Thus the front edges of the support 24, 25, 26 may be flanged so as to extend upwardly slightly above the surfaces of the insulating plates, as shown. If necessary, an auxiliary grid 20 is used in addition for increasing this effect. The process of modulation of the beam of the gun 22 by the charges 16, 17, 18 is electrostatic. In the absence of electric charges deposited at points such as 17, the potential of this surface is the same as that of the opposite conductive support 24. The electrons of the gun 22 are not deflected from their path and the fluorescent screen 21 appears luminous throughout the distance which separates two consecutive bands, that is, at 29—30. The dimensions of the luminous point so obtained are large enough. On the contrary, if charges have been deposited at points such as 17 (or 16, 18 etc.), the second beam proceeding from the gun 22 is deflected at 31, 32. Part of the electrons is absorbed by the conductor 24. The surface of the fluorescent screen 21 impinged upon is reduced at 31, 32. This reduction of the dimensions of the point (therefore of the local luminous intensity) is as 30 much more accentuated as the charge deposited upon the insulating support has been more increased. The second electron flux (gun 22) may be very intense, as this gun need not furnish, like the spot of the gun 6, a very concentrated flux; this flux is, on the contrary, uniformly distributed over the whole of the surface of the screen, and the mutual repulsion of the electrons is therefore without disadvantage. This flux is no longer concentrated on one of the successive points, as 40 is generally done in Braun tubes employed at the present day in television; therefore, there is no risk of causing the deterioration of the phosphorescent material, while maintaining an extremely intense mean luminosity which allows the projection of an image onto a large-size screen. It is interesting to note that the gun 6 may have a very low power, as small charges are sufficient for effecting the control of the second beam. The electron gun 22, which produces the 45 luminosity of the screen 21 may operate continuously. In the example described, the charges deposited at points such as 16, 17, 18 disappear progressively as a result of the imperfect insulation of the support. However, it may be advantageous to obtain the sudden discharge, immediately before the passage of the exploring beam. To obtain this sudden discharge, the following means may be employed. The insulating surface is covered with a material capable of emitting 50 secondary electrons (for example, nickel). A second scanning electronic beam is employed, which is moved in synchronism with the first but displaced with respect thereto. The electrons of this second beam are moved at a very high initial speed. By impinging upon the surface of the collector 12, the secondary electrons so released cause the charge deposited by the beam 6 modulated by the signal to disappear.

The discharge may also be effected by means 70 of a luminous or ultra-violet beam, the surface of the collector being covered with a photo-emissive substance.

I claim:

1. Receiving tube comprising a fluorescent 75 screen, a first electron gun emitting a first elec-

tronic beam, a second electron gun emitting a second electronic beam, a multi-cellular collecting grid arranged between said fluorescent screen and said first and second electron guns, said collecting grid including a series of slats of substantial width compared with the distance between them, said slats lying in planes inclined to the path of the electrons emanating from said first electron gun so as to obstruct the passage of said electrons and substantially parallel 10 to the path of the electrons emanating from said second electron gun so as to provide a substantially unobstructed passage for said electrons, each of said slats comprising bands of insulating material forming the surfaces of the slats exposed to the electrons emitted by said first electron gun and bands of conductive material forming the under surface of said slats, means associated with one of said electron guns for concentrating the beam emitted by said electron gun 20 and for causing it to scan said collecting grid to deposit charges on said bands of insulating material, means associated with the other electron gun for spreading the electronic rays emitted by said gun over the area of said collecting grid, whereby the rays of said second electron beam, in passing between said insulating slats are deflected to an extent dependent upon the charges on the parts of the strips by which they pass, and by striking the bands of conductive material 30 are absorbed in a number dependent upon their deflection.

2. Receiving tube comprising a fluorescent screen, a first electron gun emitting a first electronic beam, a second electron gun emitting a second electronic beam, a collecting grid arranged between said fluorescent screen and said first and second electron guns, said collecting grid comprising a series of supporting strips of substantial width lying in planes inclined to the path of the electrons emanating from said first electron gun and substantially parallel to the path of the electrons emanating from said second electron gun and charge receiving cells mounted on said strips, each cell corresponding to a picture point, means associated with one of said electron guns for concentrating the beam emitted by said electron gun and for causing it to scan said collecting grid to deposit charges on each of said cells, means associated with the other electron gun for spreading the electronic rays emitted by said gun over the area of said collecting grid, whereby the rays of the second electron beam passing between said strips are deflected to an extent dependent upon the charges on the cells by which they pass and, by striking the strips towards the rearward edges thereof, are adsorbed in a number dependent upon their deflection.

3. Receiving tube comprising a fluorescent screen, a first electron gun emitting a first electronic beam, a second electron gun emitting a second electronic beam, a collecting grid arranged between said fluorescent screen and said first and second electron guns, said collecting grid comprising a series of supporting strips of substantial width lying in planes inclined to the path of the electrons emanating from said first electron gun and substantially parallel to the path of the electrons emanating from said second electron gun and charge receiving cells mounted on said strips, each cell corresponding to a picture point, means associated with one of said electron guns for concentrating the beam emitted by said electron gun and for causing it 70

to scan said collecting grid to deposit charges on each of said cells, means associated with the other electron gun for spreading the electronic rays emitted by said gun over the area of said collecting grid, and screen members arranged in front of said strips for protecting said cells from the electrons of the second electronic beam, whereby the rays of the second electron beam passing between said strips are deflected to an extent dependent upon the charges on the cells by which they pass and, by striking the strips towards the rearward edges thereof, are adsorbed in a number dependent upon their deflection.

4. Receiving tube comprising a fluorescent screen, a first electron gun emitting a first electronic beam, a second electron gun emitting a second electronic beam, a collecting grid arranged between said fluorescent screen and said first and second electron guns, said collecting grid comprising a series of supporting strips of substantial width lying in planes inclined to the path of the electrons emanating from said first electron gun and substantially parallel to the path of the electrons emanating from said second electron gun and charge receiving cells mounted on said strips, each cell corresponding to a picture point, means associated with one of said electron guns for concentrating the beam emitted by said electron gun and for causing it to scan said collecting grid to deposit charges on each of said cells, means associated with the other electron gun for spreading the electronic rays emitted by said gun over the area of said collecting grid, the edges of the supporting strips facing the electron guns, being turned upwardly slightly above the charge receiving surfaces of the cells to protect said cells from the electrons emitted by said second electron gun, whereby the

rays of the second electron beam passing between said strips are deflected to an extent dependent upon the charges on the cells by which they pass and, by striking the strips towards the rearward edges thereof, are adsorbed in a number dependent upon their deflection.

5. Receiving tube comprising a fluorescent screen, a first electron gun emitting a first electronic beam, a second electron gun emitting a second electronic beam, a collecting grid arranged between said fluorescent screen and said first and second electron guns, said collecting grid comprising a series of supporting strips of substantial width lying in planes inclined to the path of the electrons emanating from said first electron gun and substantially parallel to the path of the electrons emanating from said second electron gun and charge receiving cells mounted on said strips, each cell corresponding to a picture point, means associated with one of said electron guns for concentrating the beam emitted by said electron gun and for causing it to scan said collecting grid to deposit charges on each of said cells, means associated with the other electron gun for spreading the electronic rays emitted by said gun over the area of said collecting grid, whereby the rays of the second electron beam passing between said strips are deflected to an extent dependent upon the charges on the cells by which they pass and, by striking the strips towards the rearward edges thereof, are adsorbed in a number dependent upon their deflection, said cells and said supporting strips having sufficient conductivity to form a leakage resistance permitting the charges to leak away between each successive scanning operation.

PIERRE MARIE GABRIEL TOULON.
